REGULATED DC POWER SUPPLY

BACKGROUND OF THE INVENTION

This invention relates to a regulated DC power supply which is especially effective as a DC power supply for a large current load such as an electronic computer or the electronic telephone exchanger and which is characterized in that a separate supply circuit is provided in parallel to the ordinary voltage regulating circuit. An object of this invention is to obtain a compact and economical regulated power supply by making the regulating circuit to deal only with the variable component of the load current.

Another object of this invention is to provide a transistorized regulated voltage supply of a large current capacity with a regulating circuit of a small current capacity, by supplying only one portion of the load current through the regulating circuit and regulating the remaining portion of the load current by said one portion.

A conventional regulated DC power supply comprises a variable resistance element between the source and the load, and means for detecting the output voltage from the regulated power supply per se, resistivity of said variable resistance element being controlled in response to the voltage detected by said detecting means, and the output voltage being regulated by the voltage drop across said variable resistance element.

An example of the known regulated power supply is shown in FIG. 1. The operation of the circuit shown in FIG. 1 will be described hereunder. The AC current from an AC power source E_{ac} is rectified through a transformer T_1 and a diode D_1 , charging a capacity C_1 . The rectified current i is fed to a capacity C_o connected across the output terminals. Assuming that the terminal voltage of the capacity C_1 is V_{in} and that of the capacity C_o is V_{out} , the voltage V_{in} must be higher than the voltage V_{out} by a value corresponding to the voltage drop across the variable resistance element VR as the current i flows through the element VR.

The voltage V_{out} is constantly compared with the reference voltage V_o by a comparator C which detects any variation in the voltage V_{out} and automatically varies the resistance of the element VR so as to maintain the voltage V_o at a fixed value. The voltage regulating circuit represented by the variable resistance element VR and the comparator C is usually constructed as shown in FIG. 2.

In a low voltage power supply, the variable resistance element VR in FIG. 1 is often comprised of transistors $Tr_{11}, \dots, Tr_{1n}$ and $Tr_{m1}, \dots, Tr_{mn}$. These transistors are connected all in parallel through the respective emitter resistors $R_{11}, \dots, R_{1n}$ and $R_{m1}, \dots, R_{mn}$. Variation of the output voltage V_{out} is detected after being divided by the resistors R_1 and R_2 and is compared with the reference voltage V_o . The comparator C provides the transistors with a bias current depending on the difference between the detected voltage and the reference voltage, thereby varying the internal resistances of the transistors $Tr_{11}, \dots, Tr_{1n}$ and $Tr_{m1}, \dots, Tr_{mn}$. The transistors Tr_{10} and Tr_{m0} serve to amplify the bias currents which are supplied to the transistors $Tr_{11}, \dots, Tr_{1n}$ belonging to the transistor group Tr_1 and the transistors $Tr_{m1}, \dots, Tr_{mn}$ belonging to the transistor group Tr_m respectively. Accordingly, the emitter to collector resistance of the transistors $Tr_{11}, \dots, Tr_{1n}$ and $Tr_{m1}, \dots, Tr_{mn}$ is varied depending on the variation of the output voltage V_{out} so as to suppress said variation of the output voltage.

In a low voltage and large capacity power supply used in a large electronic computer or electronic telephone exchanger, the number of transistors connected in parallel to constitute the variable resistance element as mentioned above, is often as many as several hundred. For example, in a large electronic computer which takes a DC current of 500 to 1000 A, the number of said transistors usually reaches the order of two hundred, though the number varies more or less depending on the capacity of the transistors used. Such a power supply unit is inevitably very bulky, and no attempt to reduce the size of such a unit has yet succeeded whereas there is a general tendency toward miniaturized computing circuits and memories with the aid of integrated circuits.

According to this invention, the number of transistors which constitute the variable resistance element as described above can be drastically reduced, thus reducing the size of the power unit, by controlling said variable resistance unit VR only with a current corresponding to the varied portion of the output voltage.

BRIEF DESCRIPTION OF THE DRAWINGS

10 FIGS. 1 and 2 relate to a conventional regulated DC power supply as described above;

FIG. 3 is a circuit diagram of an embodiment of the regulated DC power supply according to this invention;

FIG. 4 is a diagram for explaining the operation characteristics of the circuit shown in FIG. 3;

15 FIGS. 5 to 9 show various embodiments of this invention; and

FIG. 10 is a diagram showing a waveform related to the operation of the circuit shown in FIG. 9.

20 Throughout FIGS. 3 to 10, corresponding components are indicated by similar reference marks.

DESCRIPTION OF THE PREFERRED EMBODIMENT

Now, referring to FIG. 3, AC current from an AC power source E_{ac} is rectified by diodes D_1 and D_2 through transformers T_1 and T_2 to charge capacitors C_1 and C_2 respectively.

The voltage regulating unit which consists of the variable resistance element VR and the comparator C as shown in FIG. 1 and is constituted as shown in FIG. 2, operates so as to maintain the terminal voltage of the capacitor C_o at a fixed level.

30 Across the capacitor C_o is connected the DC load to which DC current from the voltage regulating unit AVR and DC current from the diode D_2 and the capacitor C_2 are supplied, the latter current through a resistor R. Thus, the load current i is a sum of the current i_1 from the regulating unit AVR and the current i_2 from the resistor R. Hereunder, an explanation will be made about the manner in which the circuit shown in FIG. 3 operates when the load current i varies as shown in FIG. 4 as a result of the change in the load.

40 When the load current i assumes a minimum value, the whole current i_2 is supplied through the resistor R, no current being supplied from the regulating unit AVR. If the load current i increases from the value i_2 at an instant t_1 as shown in FIG. 4, the increment $i_{11} = i - i_2$ is supplied from the unit AVR. The resistance of the variable resistance element VR included in the regulating unit AVR is adjusted depending on the terminal voltage V_{out} of the capacitor C_o so as to be kept at $V_{in} - V_{out}/i_{11}$, V_{in} being the terminal voltage of the capacitor C_1 .

45 Now, assuming that the load current i decreases at an instant t_2 , the current i_1 from the regulating unit AVR decreases from i_{11} to i_{12} , the resistance of the unit AVR changing to $V_{in} - V_{out}/i_{12}$. Thus, when the load current i varies from the maximum value i_{max} to the minimum value i_{min} , the current i_1 supplied through the regulating unit AVR varies from zero to $i_{max} - i_2$ so as to maintain the terminal voltage V_{out} of the capacitor C_o at a constant level, while a constant current i_2 is supplied to the load through the resistor R.

50 Further, a circuit as shown in FIG. 5 also is constructed according to this invention, in which each pair of two transformers T_1 and T_2 , two diodes D_1 and D_2 and two capacitors C_1 and C_2 shown in FIG. 3 is made into a single unit respectively, thus the current i_1 and i_2 being supplied from the single rectifier unit.

65 In the embodiments shown in FIGS. 3 and 5, as described above, the voltage regulating unit AVR only must have a current capacity sufficient to draw the current $i - i_2$ corresponding to the current variation in the load current i . That is, in the regulated DC power supply of this invention, it is sufficient for the voltage regulating unit to have a current capacity of a value corresponding to the expected maximum variation in the total load current, whereas in the conventional regulated DC power supply, the voltage regulating circuit must have a current capacity for the total load current. Therefore, according to this invention, a current flowing through the com-

ponents which comprise the variable resistance element can be limited to a very small value.

For example, a conventional regulated DC power supply intended for a load which consumes a current of 500 to 1,000 amperes is required to have a current bearing capacity of 1,000 amperes; while in the power supply of this invention, the voltage regulating circuit is only required to have a current capacity of 500 amperes if the variable portion of the load current is 500 amperes. Thus, the number of the transistors constituting the variable resistance element of the power supply can be reduced to one-half of that in the conventional device.

In the foregoing description, the voltage of the AC power source E_{ac} was assumed to be constant. If this voltage varies, the collector loss P_c of the transistors in the variable resistance element must be taken into consideration.

When the emitter to collector voltage of the transistors in the variable resistance element is indicated by V_{sc} and the total collector current of said transistors I_c , then it will be understood that the product $V_{sc}I_c$ must be less than the collector loss P_c . Therefore, if the voltage of the AC power source E_{ac} increases by ΔV_{in} , the following relation must be maintained:

$$(V_{sc} + \Delta V_{in}) I_c < P_c$$

Accordingly, the upper limit of the collector current will be lowered.

The above disadvantage is overcome in the embodiment shown in FIG. 6. Referring to the FIG., a parallel and reversely connected pair of thyristors SCR is phase-controlled to adjust the output of the AC power source E_{ac} . Reference marks T_1 and T_2 indicate transformers, D_1 and D_2 diodes, CH_1 and CH_2 choking coils, and C_1 and C_2 capacitors, respectively. The phase-controlled AC power is rectified through a transformer T_1 , diodes D_1 and choking coil CH_1 to charge a capacitor C_1 , and at the same time, said AC power is rectified through a transformer T_2 , diodes D_2 and choking coil CH_2 to charge a capacitor C_2 . An automatic pulse position shifter APPS controls the ignition point of the thyristors SCR depending on the terminal voltage of the capacitor C_2 . With this feedback control, the input voltage V_{in} of the voltage regulating circuit is maintained at a constant level. It will be understood that the input voltage of said automatic pulse position shifter APPS may be taken from the terminal of the capacitor C_1 instead of the capacitor C_2 .

In the embodiment shown in FIG. 7, two transformers T_1 and T_2 in the embodiment shown in FIG. 6 are combined into a single transformer T_1 . Operation of the device of FIG. 7 is similar to that of FIG. 6.

In the embodiment shown in FIG. 8, the respective pairs of transformers, diodes, choking coils and capacitors in the embodiment shown in FIG. 6 are made into respective single components indicated by marks T_1 , D_1 , CH_1 and C_1 . In this arrangement too, the feedback circuit including the pulse shifter APPS acts so as to keep the input voltage to the regulating unit AVR constant.

As described above in connection with FIGS. 6 to 8, in the regulated DC power supply of this invention which comprises a first circuit for supplying a DC current i , to the load through the voltage regulating unit AVR, a second circuit for supplying the remaining portion i_2 of the load current through the resistor R , said voltage regulating unit AVR being operated in response to the output voltage, and a rectifying circuit phase-controlled so as to maintain the input voltage to said regulating unit at a constant level, the required current capacity of the variable resistance element in the voltage regulating unit can be drastically curtailed. Thus, if the variable resistance element consists of transistors, the transistors to be connected in parallel can be reduced by as many in number, thereby providing a compact and economical regulated power supply.

Next, another embodiment of this invention will be described referring to FIG. 9.

In this embodiment of the invention, the constant component i_2 of the load current i is obtained through a thyristor SCR which is phase-controlled by the automatic pulse position shifter APPS which generates igniting pulses at a phase angle

depending on the difference between the variable component i_1 of the load current i and a reference current i_0 . That is, if the current i_1 tends to increase, the igniting angle of the thyristor SCR is shifted by means of the pulse position shifter APPS so as to increase the current i_2 . Reference marking C' indicates a comparator for providing a signal corresponding to the difference between the current i_1 and a reference current i_0 .

The operation of the circuit shown in FIG. 9 will be described hereunder with reference to FIG. 10.

It is assumed that the load current i decreases by Δi at an instant t_1 as shown in FIG. 10. The comparator C detects the rise in the output voltage V_2 due to the decrease of the load current i and controls the variable resistance element VR accordingly. Consequently, the current i_1 tends to drop to $i_1 - \Delta i$ at the same instant t_1 . The comparator C' detects said drop of the current i_1 and phase-controls the thyristor SCR according to the difference between the current i_1 and the reference current i_0 thereby to decrease the current i_2 by an amount corresponding to said decrease in the current i_1 . In the above operation, the current i_1 responds to the variation of the load current i at the instant t_1 without delay, as the comparator C and the variable resistance element VR have been selected so as to have a high speed of response. However, the response of the current i_2 will be delayed at least one-half cycle period, because the current i_2 is phase-controlled through the thyristor SCR. Therefore, if the load current i varies by Δi , the current i_1 immediately varies so as to compensate said variation Δi , and then the current i_2 varies to take over said variation Δi , thus the current i_1 is restored to the predetermined constant level. For example, if the load current i decreases at the instant t_1 , the current i_1 decreases at the same time, and then the current i_2 decreases sensing the drop in the current i_1 during the period Δt , while the current i_1 returns to the original level.

Also at the instant t_2 , if the load current i decreases, the current i_1 decreases immediately, being followed by the decrease of the current i_2 and the consequent restoration of the current i_1 . During this regulating operation, the relation represented by $i = i_1 + i_2$ is maintained among the currents.

Now, assuming that the load current i increases at an instant t_3 , the comparator C detects a drop in the output voltage V_2 due to the increase of the load current and acts so as to decrease the resistance of the variable resistance element VR, thus increasing the current i_1 . The comparator C' detects the increase of the current i_1 over the reference current i_0 and controls the pulse position shifter APPS so as to increase the conducting angle of the thyristor and therefore to increase the current i_2 . Increase of the current i_1 and i_2 raises the output voltage V_2 above the reference voltage, which in turn increases the resistance of the variable resistance element VR, thus returning the current i_1 to the normal level. That is, an increase in the load current i immediately causes a corresponding increase in the current i_1 , being followed by an increase in the current i_2 and the consequent restoration of the current i_1 to the reference level i_0 .

Generally speaking, the load current in an electronic computer or an electronic telephone exchanger varies in steps as is seen in the current i shown in FIG. 10, with a comparably small variation in each step. For such a use, the power supply of this invention is especially advantageous. That is, the variable resistance element VR is only required to have a current capacity equivalent to the sum of the reference current i_0 and the momentary rise of the load current; and if the variation of the load current at an instant, i.e., one step of the variation is small, the necessary capacity of the variable resistance element VR becomes considerably small. Therefore, according to this invention, a compact and economical regulated DC power supply is obtained.

We claim:

1. A regulated DC power supply for supplying a load with DC power, including a voltage regulating circuit having an input and an output which comprises:

means for rectifying an AC input voltage supplied to said input;

variable impedance means for receiving said rectified AC input voltage and for producing a current, the magnitude of which is controlled by the variation of said variable impedance means, said current being supplied to said output; means for controlling the variation of said variable impedance means in response to the difference between the voltage at said output and a reference voltage; means for controlling the magnitude of said AC input voltage including a phase-controlled rectifier which is phase controlled in response to the difference between the current produced by said variable impedance means and a reference current, to thereby supply said load with a controlled current, a portion of which is supplied by said phase-controlled rectifier; and a fixed impedance element connected between said phase-controlled rectifier and said output through which said portion of said controlled current is supplied.

2. A regulated DC power supply for supplying a load with

DC power comprising:

first and second circuits mutually connected in parallel between an AC power source and a load, wherein said first circuit comprises a means for rectifying the voltage produced by said AC power source;

variable impedance means including at least one transistor circuit responsive to said rectified voltage for supplying a current to said load, the magnitude of which is varied according to the difference between the terminal voltage across the load and a reference voltage; and

said second circuit comprising a phase-controlled rectifier receiving a voltage from said AC power source, responsive to the difference between the output of said variable impedance means and a reference current for controlling the magnitude of said AC voltage and for supplying said load with a controlled current in addition to the current supplied by said variable impedance means.
